JOHN LEONARD HOLMAN AND ARTHUR TREVE HOLMAN, OF CAMBORNE, CORNWALL, ENGLAND, ASSIGNORS TO HOLMAN BROTHERS LIMITED, OF CAMBORNE, CORNWALL, ENGLAND, A BRITISH COMPANY

ROCK-DRILL AND LIKE TOOL

Application filed January 19, 1929, Serial No. 333,635, and in Great Britain August 11, 1928.

This invention consists in improvements in or relating to rock-drills and like tools such as pneumatic hammers, riveters, caulkers, picks and such like and where the term "rock-drill" appears hereafter it is to be understood as including all tools by compressed fluid, such as compressed air, to which the improvements, to be described below, are applicable.

10 In tools of the above type, the compressed driving fluid is distributed to the working cylinder by means of a distributing valve whereby the driving fluid is admitted alternately to opposite ends of the main cylinder. 15 The primary object of the present invention is to improve such distributing valves.

According to the present invention the means which controls the admission of driving fluid to one or to each end of the cylinder, comprises in combination a floating plate valve, a seating on one or each side of the valve extending completely around the latter at or near its outer margin, and a fluid inlet passage for delivering fluid to the outer 25 margin of the valve (for example, an inlet passage completely surrounding the valve margin).

In a modification of the invention the distributing valve is of annular form and is 30 situated at the rear end of the cylinder surrounding a member (for example a twist bar) constituting part of the tool. It is free to move bodily between valve seats that are 35 spaced apart on opposite sides of it, and so constitutes a floating valve, as distinct from the known type of hinged valve employed heretofore which is constrained to swing about a fixed axis.

40 Preferably where the valve is of annular form its inner periphery is made to constitute a bearing surface by which the valve is guided in engagement with an inner member constituting a part of the tool. This member may be a sleeve surrounding the 45 twist bar above-mentioned.

In one example of the invention, the valve has an axial extension of annular form affording by its inner periphery an additional bearing surface extending on one or 50 both sides of the valve. The total length

of the bearing surface is thus increased beyond that which would be afforded by the thickness of the valve-plate alone. This axial extension may also help to balance the pressures on the two sides of the valve in a 55 manner to be described hereinafter.

In order that the invention may be more readily understood one preferred example of rock-drill and a modification thereof embodying the features of the invention, will now 60 be described with reference to the accompanying drawing, in which:—

Figure 1 illustrates diagrammatically in section those parts of a rock-drill necessary to the understanding of the invention; and 65

Figure 2 shows a modified form of a portion of the apparatus shown in Figure 1.

Like reference numerals indicate like parts in the drawing.

The rock-drill comprises a main hammer 70 cylinder 10 having a hammer piston 11 reciprocating therein. A twist-bar or rifle-bar 12 extends coaxially into the cylinder from its rear end and engages a correspondingly fluted aperture formed coaxially in the piston. The twist-bar is associated with the usual or any preferred form of mechanism, such, for example, as ratchet mechanism, designated as a whole by the numeral 13, whereby a partial rotation is imparted to the 75 piston as it moves in one direction, but when it moves in the reverse direction no such partial rotation is effected.

All these parts are of well-known construction and arrangement.

Surrounding the twist-bar or its equivalent is an annular valve-casing 14 within which is situated an annular plate-valve 15.

At the rear end of the drill there is a main inlet passage 16 for driving fluid and in the 90 passage there is a main control cock therefor (not illustrated). The passage 16 communicates with the interior of the valve-chamber 17 which contains the valve 15 and the outer diameter of which is greater than the outer 95 diameter of the valve 15 so that there is a clearance between the outer wall of the chamber and the outer margin of the valve. Opposed valve-seats 18, 19 are provided in the valve-chamber, and in the valve-seats there 100

are provided annular ports 20, 21 communicating respectively with passages 22, 23 opening into opposite ends of the cylinder.

In recesses situated behind the valve-chamber are accommodated two pressure-release-valves 32 and 33. From near one end of the cylinder a passage 30 communicates with a port 34 that is controlled by one face of the valve 32; and an exhaust port 36 is controlled simultaneously by the same face thereof. The other valve 33 controls in a similar manner by its one face an exhaust port 37 and a port 35 which communicates with a passage 31 opening into the cylinder near its opposite end. Ports 38 and 39 which are controlled by opposite faces of the valve 15 lead to the other faces of the valves 32 and 33 respectively. When either of the ports 38 or 39 is uncovered driving fluid forces the corresponding release-valve firmly on to its seating, thus closing the connection between its release-passage (30 or 31) and exhaust.

In order partly to balance the pressures on the two sides of the valve 15 an annular cavity 40 is provided connected with the valve chamber 17 by a passage 41. The pressure exerted by the driving fluid in this cavity in a rearward direction tends to balance the pressure of the driving fluid acting in a forward direction on the other face of the valve.

The valve 15 is provided with a cylindrical extension 45 which is accommodated in a recess 47 shaped to receive it as a sliding fit. This cylindrical extension serves two purposes. Firstly, it guides the valve and prevents it from tilting, and secondly it helps further to effect the balance of the valve. The rear end of the recess 47 opens through a passage 49 to exhaust. The guiding of the valve 15 is effected by the external surface of the extension 45 and also by its internal surface and that of the valve-plate itself. The internal surfaces of the valve-plate and extension form an extended bearing surface which engages with the outside surface of a sleeve 50 surrounding the rifle-bar 12.

It is convenient in this construction to provide the usual water-tube 51.

The operation of the drill is as follows:— It is assumed that, at the commencement of the cycle of operations, the distributing valve 15 is at the front end of its stroke and the ports 20 are opened by the distributing valve which will also open the port 39 admitting driving fluid to the pressure-release-valve 33. The release-valve 33 is thereby held on its seating so as to close communication between its pressure-release-passage 31 and exhaust port 37. The other pressure-release-valve 32 will, however, have opened its appropriate release-passage 30 to exhaust and the piston 11 will commence to move rearwardly in the cylinder. As it does so air is mainly expelled during the first portion of the stroke of the piston through an open ex-

haust port 48, situated approximately midway in the cylinder wall. Further passage of the piston closes this port and release of the air from the leading face of the piston takes place through the release-passage 30. Before the end of the piston-stroke this release-passage is closed by the piston and pressure will accumulate behind the piston and in front of the main valve. Almost immediately after the closing of the passage 30, the trailing edge of the piston uncovers the open exhaust port 48 causing a sudden drop in pressure in the front end of the cylinder, in the passage 22 and on the rear face of the valve. This sudden drop of pressure combined with the accumulation of pressure in the rear end of the cylinder and the ports 21 causes the valve to fly over on to its other seat.

This movement of the valve 15 will close the port 39 leading to pressure-release-valve 33 and open the port 38 leading to pressure-release-valve 32. This will close the valve 32 on to its seating and permit the valve 33 to open immediately pressure is exerted upon it (through the release-passage 31) as the piston commences to move towards the front end and after the main exhaust port 48 has again been closed.

It will be appreciated that when the valve 15 is in the position shown, the whole of the area of one face of it which lies outside the boundary of the axial extension 45 is subjected to the full fluid-pressure. If the extension 45 were omitted, as it may be in a modified form of the invention, the whole area of one face of the valve would be subjected to this pressure.

The provision of the cavity 40 enables air pressure to act on the opposite face of the valve and so partially balance the pressures on the two faces. Thus, at the end of the rearward stroke of the piston it is only necessary for a comparatively small pressure to be accumulated by the last portion of the piston travel and/or a small dissipation of the pressure through the passage 22 to throw the valve 15 very rapidly on to its other seat.

By the provision of the extension 45 the area of the rear face subjected to the full fluid-pressure is reduced, and a better balance of the pressures on the two valve faces is thus obtainable than would be possible were the extension 45 not present as in the above contemplated modification. The provision of the passage 49 allows the extension 45 freedom of movement in the recess 47.

In the modification illustrated in Figure 2, the rear end of the recess 47, instead of opening to exhaust, is connected by a passage 55 to a port 56 in the seating of the release valve 32 containing the ports 34 and 36.

A passage 57 is provided in the side of the recess 47 connecting it to the passage that terminates in the port 38. Thus, driving fluid

is admitted from the port 38 to the end-face of the axial extension 45 of the valve when the latter is in the rearward position, i. e. at the end of its stroke opposite to that shown in Figure 2. Thus, with the valve in its forward position, as illustrated, the end-face of the extension 45 is connected through the passage 55, port 56 and port 36, to exhaust, thus favouring a rapid rearward movement of the valve as before. When, however, the valve 15 moves rearwardly to admit air for the forward stroke of the piston 11 the port 38 is opened, the valve 32 is forced on to its seating and the full driving fluid-pressure is admitted to the end of the extension 45 through the passage 57 thus favouring a rapid forward movement of the valve 15. This overcomes any tendency which the valve 15 might otherwise have to stick as, for example, when boring a tight hole which results in considerable reduction in the speed of the piston 11.

We claim:—

1. For a rock-drill or like tool, means which, for controlling the admission of driving-fluid to opposite ends of the cylinder, comprises, in combination, an annular valve-chamber that is coaxial with the cylinder, an internal guide-member, an annular distributing valve which surrounds and engages said internal guide-member, valve-seats spaced apart on opposite sides of the valve wherein the valve is free to move bodily between said valve seats and lies in a plane transverse to the cylinder axis, a fluid inlet passage for delivering driving-fluid to the outer margin of the valve from which it can pass to either side of the valve, and an axial extension on the valve, which extension affords an additional bearing surface, and whereby the areas of the two opposite valve faces are unequal.

2. For a rock-drill or like tool, means which, for controlling admission of driving-fluid to opposite ends of the cylinder, comprises, in combination, an annular valve-chamber that is co-axial with the cylinder, a recess in said valve-chamber from which driving-fluid is excluded, a floating plate-valve therein that is bodily movable in the direction of the cylinder axis, and lies in a plane transverse to the cylinder axis, a seating on each side of the valve approximately at its outer margin, and a fluid inlet passage for delivering driving-fluid to the outer margin of the valve from which it can pass to either side of the valve, and an axial extension on the valve which extension is a sliding fit in said recess from which driving-fluid is excluded, and whereby the effective area of one face of the valve as compared with that of the other face is reduced.

3. For a rock-drill or like tool, means for controlling admission of driving fluid to opposite ends of the cylinder comprising the combination of parts according to claim 2,

and, in the valve chamber, an internal guide-member which is co-axial with the cylinder and on which the valve is a sliding fit, wherein in the recess in which the axial extension is a sliding fit is closed except for a passage **70**

4. For a rock-drill or like tool, means for controlling admission of driving fluid to opposite ends of the cylinder, comprising the combination of parts according to claim 2, **75** with an internal guide member in the valve chamber on which guide member the valve is a sliding fit, wherein the recess in which the said axial extension is a sliding fit is alternately put into communication with the full **80** driving-fluid pressure and the exhaust.

5. For a rock-drill or like tool, means for controlling admission of driving fluid to opposite ends of the cylinder, comprising the combination of parts according to claim 1, **85** with a recess in the body of the valve chamber in which the axial extension is a sliding fit, and from which driving-fluid is excluded.

6. For a rock-drill or like tool, means for controlling admission of driving fluid to opposite ends of the cylinder, comprising the combination of parts according to claim 1, and in the body of the valve casing, a cylindrical recess in which the said axial extension is a sliding fit. **95**

7. For a rock-drill or like tool, means for controlling admission of driving fluid to opposite ends of the cylinder, comprising the combination of parts according to claim 1, in the body of the valve casing, a cylindrical **100** recess in which the said axial extension is a sliding fit and which is closed except for a passage connecting its interior with the exhaust.

8. For a rock-drill or like tool, means for controlling admission of driving fluid to opposite ends of the cylinder, comprising the combination of parts according to claim 1, and, in the body of the valve casing, a cylindrical recess in which the said axial extension is a sliding fit and which is alternately put into communication with the full driving fluid pressure and the exhaust. **105**

9. A valve assembly comprising in combination an annular valve-chamber that is co-axial with the cylinder, an internal guide member in said chamber, an annular distributing valve having a hollow cylindrical axial extension which valve surrounds and engages said internal guide-member, annular valve-seats spaced apart on opposite sides of the valve at or near its outer margin wherein the valve is free to move bodily between said valve seats and lies in a plane transverse to the cylinder axis, a fluid inlet-passage for delivering driving-fluid to the outer margin of the valve and completely surrounding that margin from which it can pass to either side of the valve, and a recess in the body of the valve-casing, in which recess the axial exten- **115**

sion on the valve is a sliding fit, and from which driving-fluid is excluded and which is closed except for a passage connecting the interior of the recess with exhaust, whereby the effective area of one face of the valve as compared with that of the other face is reduced.

10. A valve assembly comprising in combination an annular valve-chamber that is coaxial with the cylinder, an internal guide member in said chamber, an annular distributing valve having a hollow cylindrical axial extension, which valve surrounds and engages said internal guide-member, annular valve-seats spaced apart on opposite sides of the valve at or near its outer margin wherein the valve is free to move bodily between said valve seats and lies in a plane transverse to the cylinder axis, a fluid inlet-passage for delivering driving-fluid to the outer margin of the valve and completely surrounding that margin from which it can pass to either side of the valve, and a recess in the body of the valve-casing, in which recess the axial extension is a sliding fit, and which is alternately put into communication with the full driving-fluid pressure and exhaust.

In testimony whereof we have signed our names to this specification.
